(57) **CLAIM**

I claim the ornamental design for a top member for tile leveling device, as shown and described.

DESCRIPTION

FIG. 1 is a top-front perspective view of a top member for a tile leveling device according to an embodiment of the invention.

FIG. 2 is a top view of the top member of FIG. 1.

FIG. 3 is a bottom view of the top member of FIG. 1.

FIG. 4 is a front view of the top member of FIG. 1.

FIG. 5 is a rear view of the top member of FIG. 1.

FIG. 6 is a left view of the top member of FIG. 1; and,

FIG. 7 is a right view of the top member of FIG. 1.

The portions of the top member for tile leveling device shown in broken lines are included for the purpose of illustrating environment and form no part of the claimed design. The portions of the top member for tile leveling device shown in broken lines having unequal length segments illustrate the boundary of the claimed design and form no part of the claimed design.
